UNITED STATES PATENT OFFICE.

CHARLES L. BUCKINGHAM, OF DENVER, COLORADO.

ORE-PULVERIZING MILL.

1,247,633.

Specification of Letters Patent. Patented Nov. 27, 1917.

Application filed January 30, 1917. Serial No. 145,418.

To all whom it may concern:

Be it known that I, CHARLES L. BUCKINGHAM, a citizen of the United States of America, residing at the city and county 5 of Denver and State of Colorado, have invented a new and useful Ore-Pulverizing Mill, of which the following is a specification.

My invention relates to improvements in 10 ore crushing, grinding, and pulverizing mills, and the objects of my invention are:

First, to provide an operative Chilian mill in which tired ore crushing rolls are provided with oppositely arranged trunnion 15 shafts that are journaled in journal boxes positioned in semi-circular casings that surround the upper portion of the ore crushing rolls, and in which said rolls are pushed around the ore crushing surfaces of the mill 20 and rest squarely on top of it and on the ore thereon.

Second, to provide a Chilian mill in which the rolls are pushed around upon a die ring and bear naturally and freely on it with 25 their whole weight, and in which a multiple number of rolls travel over irregular layers of ore on the die ring independently of each other. And

Third, to provide a simple, practical and 30 powerful ore pulverizing mill having numerous novel features that will be fully described in the accompanying specification.

I attain these objects by the mechanism illustrated in the accompanying drawings, 35 in which:

Figure 1 is a side elevation of the improved ore pulverizing mill.

Fig. 2 is a plan view thereof, the feed hopper being removed.

Fig. 3 is a vertical sectional view of the same.

Fig. 4 is a front view of one of the roll housings or casings.

Fig. 5 is a bottom plan view of the same.

Fig. 6 is an end view thereof.

Fig. 7 is a vertical, longitudinal sectional view of one of the roller shaft journal boxes.

Fig. 8 is an end view of the same.

Fig. 9 is a vertical sectional view through 50 a portion of the ore pan and one of the screen frames, showing how the screen frame fits within an opening in the said ore pan, and the means for clamping the same to said pan.

Fig. 10 is a perspective view of the launder with surrounds the lower end of the ore

pan, in position to catch the screened products therefrom.

Fig. 11 is a side view of one of the halves of the launder, showing more clearly the 60 manner of securing the parts together.

Fig. 12 is a plan view of the feed hopper. And

Fig. 13 is a view of a portion of one of spider arms.

Similar letters of reference refer to similar parts throughout the several views.

Referring to the drawings:

The numeral 1 designates a hollow base that forms the foundation casting of my 70 mill; 2 designates the ore crushing pan which comprises an outwardly flaring marginal wall extending around a raised central conical hub portion; 3 designates a housing band or casing that is connected to 75 the upper edge of the pan and extends above it and is adapted to confine the ore to the pan; 4 designates the feed hopper, with three ore feeding spouts that centrally support it, as will be fully explained hereinafter; 5 designates the driving shaft; 6 designates the power driven shaft. The ore crushing pan is provided with screens 7, which are secured over screen frames 8, having rectangular projections which fit into openings 9 in 85 the wall of the pan, and the frames are clamped to the pan by wedges 10 that are driven into recessed lugs in plates 11, which are riveted to the pan between the adjacent ends of each two screens, the wedges bearing 90 against the ends of the screen frames, and below these screens a circular launder 12 is secured, that surrounds the lower end of the pan and rests on the top of the base. This launder catches the screened product 95 from the pan and discharges it through a spout from the machine, and it is conveyed to other machines for further treatment.

My improved mill belongs to the type of ore crushing and pulverizing machines 100 known in the mining industry as Chilian mills, and some of the above enumerated parts are used in some form in the Chilian mills at present in use, and are consequently parts that are used in all or most all Chilian 105 mills.

My invention, however, contemplates new, novel and important improvements in the construction and arrangement of these parts and of the parts of them that coöperate to 110 make an operative Chilian mill.

In the bottom of the pan 2, a grinding or

die ring 13 is placed, which is made of the hardest steel obtainable, that is suitable for this purpose. This die ring 13 extends entirely around the bottom of the pan, and is thick enough to wear for a long time under the action of ore crushing rollers 14, which rest upon said die ring and are rolled around the pan by the vertical driving shaft 5, as will be presently described.

16 The wall and conical portion of the pan are surrounded on each side of the die rim by circular lining plates or rings 15 and 16 respectively, of steel or other suitable material, the upper edge of the ring 15 terminating below the screen frame openings.

17 The ore receiving pan is secured to the base by bolts 17, and the screenings launder is preferably made in two equal sections, which are bolted together around the bottom 20 of the pan, and rest on a projecting annular lip 18 of the base. The rolls 14 are of the tired type used in modern practice for crushing ore, and consist of cast iron or steel roll centers or disk portions, upon the 25 periphery of which ore crushing rings or tires 14^a of the hardest steel are secured.

18 The roll centers of the ore crushing rolls, of which there are three, are provided with axial bores, in each of which a shaft 19 is rigidly secured in any suitable manner. Each of these shafts projects from the opposite sides of its roll center far enough to form trunnions 20 of equal length. The 30 trunnions of each roller are mounted in journal boxes 21, which are provided with brass bushings 22, which surround the trunnions 20.

19 Each box 21 comprises a hub portion having an integral surrounding projection 23, 40 which is concentric with the hub at its upper end, but merges into straight parallel sides, its lower end being a flat horizontal surface, as clearly shown by Fig. 8. The surfaces of these projections 23, are rounded or substantially semi-circular in cross section, and are mounted in correspondingly shaped slideways 24, formed in projections 25, on opposite sides of semi-circular housings 26, which fit loosely over the upper halves of 45 the rolls 14. One end of the inner side of each housing 26, is formed with a vertical plate or flange 27, which is provided with bolt holes 28, arranged as shown in Fig. 4; the face of the flange being at an inclination 50 to the inner side of the housing. Upon the opposite end of the inner side of the housing is formed a hollow segmental extension 29, which is open at the bottom and arched over at the top thereof. The outer wall of this 55 extension terminates at its lower edge in an outwardly projecting curved horizontal web or plate 30, which is integrally united with the adjacent end of the housing and thus serves as a brace for the said extension. The 60 free end of the extension and its web ter-

minates in a vertical flange 31, which is provided with bolt holes 32, the latter flange being at an opposite inclination to that of the flange 27. Upon the inner wall of the extension 29, adjacent to its free end, is formed a U-shaped projection 33, which surrounds an opening 34, in the said wall, and a vertical aperture 35 is formed through the extension adjacent to its connection with the housing, through which a suitable 75 scraper, not shown, is inserted.

76 An inwardly extending wing or plate 36, is formed on the inner projection 25, of the housing, for a purpose to be presently shown. When the housings are placed in position over the rolls, the flange 27, of each housing, is bolted to the flange 31 of the adjoining housing, as shown by Fig. 2, so that the three housings are rigidly secured together, and they are so arranged that their axes are out of radial lines with, or tangent to the axis of the vertical shaft 5, as shown, this arrangement tending to minimize the centrifugal force exerted upon the rolls. Upon the upper end of the shaft 5 is keyed a spider 37, comprising a hub from which projects three curved arms. The outer ends of these arms have flange portions 38, upon which are secured wear plates 39 and the wings 36 on the housings are provided with 80 similar wear plates 40.

85 The ends of the spider arms having the wear plates, bear against the wear plates of the said wings 40, so that when the shaft 5 is rotated the housings are revolved thereby, 90 through their engagement with the spider arms.

95 The U-shaped projections 33 on the housing extensions support the free ends of the depending spouts 41, which are integrally 105 connected to the hopper 4, which is thus supported above the said extensions and in axial line with the shaft 5. The spouts register with the holes 34 in the extensions, so that material fed to the hopper passes through 110 the spouts 41 and holes 34 to the interior of the extensions and drops down upon the die rings, as will be understood by reference to Fig. 3.

115 The hopper is provided with a central tube or sleeve 43, which extends above the rim of the said hopper, and through this sleeve is passed an oil pipe 44, the lower end of which is screwed into the counterbored end of an axial oil hole 45 in the shaft 5, 120 the said hole extending down below the upper end of the conical hub portion of the pan, and intersecting lateral holes 46, which extend through the periphery of the shaft. In this way oil is fed to the bore of the conical hub and around the shaft 5. The lower end of the shaft 5 is mounted in a bearing 47, on the base 1, and a bevel gear wheel 48 is keyed to the shaft, which is driven by a bevel pinion 49, on the inner end of the 125 130

power shaft 6. The outer end of this shaft is mounted in a bearing 50, and the shaft is provided with fast and loose pulleys 51 and 52, respectively.

5 The projections 25, on the housings are provided with oil holes 53, which register with similar holes in the journal boxes 21, and the holes 53 are provided with capped oil pipes 54, by which oil can be fed to the boxes.

10 In operation, the shaft 5 is rotated by its gear wheel 48, which is driven by the pinion 49, on the power shaft 6, and the spider on the upper end of the shaft 5 engages and 15 revolves the housings 26 in which are mounted the rolls 14 which travel on the die ring 13. Crushed ore and water is then fed to the hopper 4, from which it passes out through the spouts 41 to the extensions 29 20 and down upon the die ring 13 and into the trough of the pan formed by the lining rings 15 and 16. As the rolls revolve the ore is finely pulverized and the pulverized ore and water passes out through the screens 7, the 25 screened product being caught in launder 12, whence it is conveyed to other machines for further treatment.

The construction above described provides a mill of the Chilian type in which the rolls 30 have double bearings in vertically adjustable journal boxes which are mounted in connected housings which are automatically raised and lowered to conform to the varying depths of ore on the die ring, and the rolls 35 being independently adjustable are thus enabled to rest squarely on the die ring at all times.

Having described my invention, what I claim as new and desire to secure by Letters Patent, is:

40 1. In an ore mill of the character described, the combination with a pan, a die ring therein and a shaft axially mounted in said pan, of rolls adapted to run on said die ring, housings for said rolls having slidable bearings in which said rolls are mounted, arms connected with the shaft for revolving said housings, and means for rotating said shaft.

45 2. In an ore mill of the character described, the combination with a pan, a die ring in said pan and a shaft axially mounted in said pan, of rolls adapted to run on said die ring, having trunnions, connected housings for said rolls, and bearings slidably mounted in said housings in which said trunnions are mounted, arms connected with the shaft for revolving said housings, and means for rotating said shaft.

50 3. In an ore mill of the character described, the combination with a pan, a die ring therein and a power driven shaft axially mounted in said pan, of rolls adapted to run on said die rings having trunnions, connected housings for said rolls having

slideways, bearings mounted in said slideways in which said trunnions are mounted, arms connected with the shaft for revolving said housings, said housings being vertically and automatically adjustable independently of the said arms.

5 4. In an ore mill of the character described, the combination with a pan, a die ring therein and a power driven shaft axially mounted in said pan, of rolls adapted to run on said die ring having journals, connected housings for said rolls having vertically slidable journal boxes in which said journals are mounted, and arms carried by said shaft and in slidable engagement with said housings for revolving them.

10 5. In an ore mill of the character described, the combination with a pan, a die ring therein, an axial shaft rotatably mounted in said pan and rolls adapted to run on said ring having journals extending from their opposite sides, of connected semi-circular housings having slideways, automatically adjustable journal boxes in said slideways in which the roll journals are mounted, a spider rigidly mounted on said shaft having portions which engage said housings, said housings being vertically and automatically adjustable independently of said spider, a hopper and spouts connecting the same with said housings and means for rotating said shaft.

15 6. In an ore mill of the character described, the combination with a pan, a die ring therein, a shaft axially mounted in said pan, and rolls adapted to travel on said die ring, of connected semi-circular housings having slidable bearings in which said rolls are mounted and feed apertures, abutments on said housings, a spider rigidly mounted on said shaft having portions which engage said abutments, a hopper having feed spouts connected with said feed apertures, said apertures being arranged to discharge in advance of said rollers, and means for rotating said shaft.

20 7. In an ore mill of the character described, a pan having an axial shaft rotatably mounted therein, a die ring in said pan, rolls on said die ring having trunnions on their opposite sides, connected semi-circular housings having vertical slideways in their opposite walls, journal boxes on said trunnions which are mounted in said slideways, wear plates on said housings, a hub rigidly mounted on said shaft having arms which engage said wear plates whereby said housings are revolved by but not connected with said shaft, and have a vertical movement independently of said arms, and means for rotating said shaft.

25 8. In an ore mill of the character described, a plurality of semi-circular housings, each having a hollow open bottom extension on one end which is bolted to the

- adjoining end of the next housing, said extensions having feed openings and semi-circular seats extending from said openings, slideways in the opposite walls, of said housings, which extend through their lower edges, rolls having trunnions, and bearing boxes thereon which are mounted in said slideways, a die ring upon which said rolls travel, a pan supporting said die ring, a power driven shaft axially mounted in said pan, arms on said shaft unconnected with but in engagement with said housings for revolving them, and a hopper having spouts, the lower ends of which rest in said seats.
9. In an ore mill of the character described, the combination with a pan, a die ring therein and a driving shaft axially mounted in said pan having arms extending from its upper end, of semi-circular connected housings, slideable bearings in said housings, and rolls on said die rings having trunnions mounted in said slideable bearings, and plates on said housings which are engaged by said arms, said arms being unconnected with said housings.
10. In an ore mill of the character described, the combination with a pan having
- an axial shaft rotatably mounted therein, a die ring and rolls adapted to travel on said die ring, having journals extending from their opposite sides, of semi-circular housings for said rolls having oppositely disposed slideways and boxes in said slideways in which said journals are mounted, hollow extensions on one end of each of said housings which are bolted to the other end of the adjoining housing, said extensions being open at the bottom and provided with apertures in their inner walls, U-shaped projections surrounding said openings, a hopper having depending spouts, the ends of which rest in said U-shaped projections and register with the said openings, a spider rigidly secured to said shaft and having portions which engage said housings, whereby when the shaft is rotated the housings with their rolls are caused to revolve, and means for rotating said shaft.

In testimony whereof I affix my signature in presence of two witnesses.

CHARLES L. BUCKINGHAM.
